C. G. CUNNINGHAM,
LUBRICATING DEVICE,
APPLICATION FILED MAR. 29, 1917.

1,386,604.

Patented Aug. 9, 1921.

UNITED STATES PATENT OFFICE.

CHARLES G. CUNNINGHAM, OF NEW YORK, N. Y., ASSIGNOR TO ELEVATOR SUPPLIES CO., INC., A CORPORATION OF NEW JERSEY.

LUBRICATING DEVICE.

1,386,604.

Specification of Letters Patent.

Patented Aug. 9, 1921.

Application filed March 29, 1917. Serial No. 158,213.

To all whom it may concern:

Be it known that I, CHARLES G. CUNNINGHAM, a citizen of the United States, residing in New York, in the county and State of New York, have made a certain new and useful invention in Lubricating Devices, of which the following is a specification.

This invention relates to lubricating devices and particularly to devices of this nature which are mounted on a moving body, operating along a guide, or the like, to lubricate said guide, or the like, by the swaying movement of the moving body relative thereto.

The object of the invention is to provide a lubricating device which is simple in structure, efficient in operation, and economical of manufacture.

Further objects of the invention will appear more fully hereinafter.

The invention consists substantially in the construction, combination, location and relative arrangement of parts, all as will be more fully hereinafter set forth, as shown in the accompanying drawing and finally pointed out in the appended claims.

Referring to the drawing:

Figure 1 is a view in side elevation of the lubricating device applied to the moving body, showing it in assembled relation, relative to the guide.

Fig. 2 is a view in perspective of the same.

Fig. 3 is a sectional view taken on the line 3—3, Fig. 2, and looking in the direction of the arrows.

Fig. 4 is a sectional view taken on the line 4—4, Fig. 3 and looking in the direction of the arrows.

Fig. 5 is a sectional view, taken on the line 5—5, Fig. 3, and looking in the direction of the arrows.

The same part is designated by the same reference numeral wherever it occurs throughout the several views.

In my Patent No. 1,181,438, issued to me May 2, 1916, I show and describe a lubricating device which is mounted on a moving body, such as an elevator, and is operated by the swaying movement of the moving body relative to a fixed guide to pump a lubricant contained therein to the surface of the guide. It is to structural features of a lubricating device of this nature, which has various ad-

vantages over the structure shown and described in my patent above identified, that the present application is directed.

In the drawing I show the fixed guide at 1 along which operates the moving body, such as the elevator, or counter weight thereof indicated at 2, and upon which is mounted the lubricating device indicated generally at 3, to be operated by the swaying movement of the moving body 2, relative to the fixed body or guide 1, to supply the guide with a lubricant to facilitate the movement of the moving body therealong. The lubricating device 3 may be secured to the moving body in any desired manner. I show a simple arrangement wherein a bracket indicated at 4 is secured to the moving body, to which bracket the lubricating device 5 is suitably secured, for example by bolts 6.

In its essential characteristics the lubricating device consists of the tank 3, having a chamber 7 to contain the oil or other lubricant. The tank is formed with a transverse pump chamber 8 at its lower end, in which reciprocates a plunger piston 9 located wholly within the tank. This plunger is firmly but yieldingly pressed outwardly by a spring 10; the pump chamber 8 communicates with the oil chamber 7 through an opening 11 which if desired may be controlled by a valve, such as the ball valve shown. Through the vertical wall or an enlarged rib 12 of the tank 3 is formed a duct or passage 13, which if desired, may be controlled by a valve such as the ball which sits toward the pump chamber. This duct or passage communicates at its lower end with the pump chamber 8 and is interiorly threaded at its upper end to receive a screw plug 15. This screw plug is kerfed in one side thereof as indicated, and preferably at an incline to the longitudinal access of said plug to form a passage 50. At or near its upper end the wall of the duct 13 is provided at diagrammatic opposite points with perforations opening respectively into the oil chamber 7, and to the chamber 16, in which is located suitable packing or oil-absorbing material, such as felt or the like, as indicated at 17. This chamber in which the felt or packing material is carried is arranged to straddle the guide 1 or other surface to be lubricated, and said chamber is opened at the sides there-

of presented to the surface to be lubricated so that the felt or other packing material operates in contact with said surface.

It will be seen that thus far the construction of the lubricating device 3, with the exception that the pump plunger 9 does not extend through the exterior wall thereof, is identical with the structure shown and described in my patent hereinbefore identified.

10 Within the oil chamber 7 of the tank 3 I form lugs 20, preferably cast integral therewith. These lugs have a central slot therein indicated at 21, Fig. 3, to receive a pin 22 carried by a lever 23. The lever 23 is an 15 angle lever with one arm extending downwardly and bearing against the end of the plunger 9, the other arm extending upwardly at an angle to the first arm center to allow the first arm to move the plunger 8 20 toward the chamber 8 against the action of the spring 10 when the upper arm is moved, the entire angle lever acting about its pivotal support formed by the pin 22 and the slot 21 of the lugs 20.

25 A suitable cover 25 is provided, which cover may be removed by unscrewing the screws 26 to allow access to the pad chamber 16. The cover 25 is provided with a channel portion 27 in which is mounted to move 30 therein a push rod 28. This push rod may be of any desired shape or material, but I prefer to make the same of the same shape as the channel 27 and to provide one end thereof with a fiber head 30. The other end 35 of the member bears against the upper arm of the angle lever 23, as shown best in Fig. 3.

40 A liftable cover carried by lugs 31 on the exterior of the tank 3 is shown at 33 which 45 cover is of the same contour as the cover 25, so that together therewith the entire contents and the internal mechanism of the device is completely inclosed and therefore 50 dust and dirt proof. It will be seen that access to the chamber 7 of the tank is readily secured through the cover 33 so that oil may be readily supplied thereto to allow access to the adjusting screw 15 on the groove or provide a slot through the slideable member 55 50 as indicated at 40. Thus it will be seen to gain access to the adjusting screw 15, it is merely necessary to lift the hinged cover 33 as will be readily understood.

With this construction of lubricator it will 55 be seen that I provide a lubricating device which when swaying with the moving body relative to its fixed guide, the end of plunger 30 will contact with the guide, thereby 60 operating the lever 23 to operate the pump plunger 9 and force the oil up to the pad 17, which being in contact with the guide, lubricates the same. However, through the pas-

sage 50 through the walls of chamber 13, any surplus oil or lubricant pumped to the pad 17 will drain back into the oil chamber 7, 65 as shown.

It will be seen therefore, that I have provided a lubricating device which is simple in structure, efficient in operation and in which there are no parts which can get out of adjustment or be inadvertently or otherwise rendered inoperative.

Further, the use of packing is eliminated as there are no parts extending through the 75 wall of the tank.

Having now set forth the objects and nature of my invention and having shown and described a structure embodying the principles thereof, what I claim as new and useful and of my own invention and desire to 80 secure by Letters Patent is:

1. A lubricating device comprising an oil receptacle, an oil distributing mechanism lying wholly within said receptacle, a slideable plunger mounted on the top of the receptacle for operating the oil distributing mechanism through the swaying movements of the receptacle, said slide and operating plunger also inclosed by protective casing.

2. The combination with a guide, of a lubricating device comprising an oil receptacle and a pump chamber communicating therewith, a plunger operating in said chamber and lying wholly within said receptacle, a spring opposing the operation of said plunger in one direction, an angle lever pivotally carried at a point intermediate its ends by the interior wall of said receptacle and bearing at one end against said plunger, and means operated by the swaying movement 100 of the lubricating device relative to said guide for exerting a pressure on the other end of said lever.

3. A lubricating device comprising a single hollow casting to contain oil, a pump chamber formed in the wall of said casting and communicating with the hollow portion of said casting, said casting also being provided with a chamber to receive a distributing pad, a duct formed in the casting to provide a communication between said pad and pump chambers, a plunger located in said pump chamber, a lever pivotally supported in the hollow portion of the casting and bearing at one end against said plunger, 110 means normally tending to yieldably maintain said plunger in retracted position in said pump chamber, and means slidably mounted on the top of said casting for rocking said lever.

115 In testimony whereof I have hereunto set my hand on this 26th day of March, A. D. 1917.

CHARLES G. CUNNINGHAM.
